US0D1087968S

(12) **United States Design Patent** (10) **Patent No.:** **US D1,087,968 S**
(45) **Date of Patent:** **** Aug. 12, 2025**

(54) **ELECTRONIC DEVICE**

(71) Applicant: **Elo Touch Solutions, Inc.**, Knoxville, TN (US)

(72) Inventors: **David Noppenberger**, Baltimore, MD (US); **Wei Wang**, Suzhou (CN); **Xingdong Zhao**, Suzhou (CN); **Hui Yang**, Suzhou (CN)

(73) Assignee: **Elo Touch Solutions, Inc.**, Knoxville, TN (US)

(**) Term: **15 Years**

(21) Appl. No.: **29/921,303**

(22) Filed: **Dec. 15, 2023**

Related U.S. Application Data

(63) Continuation of application No. 29/893,442, filed on May 30, 2023, now Pat. No. Des. 1,015,329, which is a continuation of application No. 29/816,051, filed on Nov. 18, 2021, now Pat. No. Des. 994,664.

CLAIM

The ornamental design for an electronic device as shown and described.

DESCRIPTION

FIG. 1 is a top front perspective view of an electronic device showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a top rear perspective view showing the electronic device of FIG. 1 in a configuration of use; and,

FIG. 10 is a right side view thereof.

The broken lines in the figures show portions of the electronic device that form no part of the claimed design.

1 Claim, 8 Drawing Sheets
